US0D1110898S

(12) **United States Design Patent** (10) Patent No.: **US D1,110,898 S**
(45) Date of Patent: ** Feb. 3, 2026

(54) **GRILLE FOR AUTOMOBILE OR REPLICA THEREOF**

(71) Applicant: **ASTON MARTIN LAGONDA LIMITED**, Warwick (GB)

(72) Inventors: **Miles Nurnberger**, Warwick (GB); **Julian Nunn**, Warwick (GB); **Jiaqi Han**, Warwick (GB)

(73) Assignee: **Aston Martin Lagonda Limited**, Gaydon (GB)

(**) Term: **15 Years**

(21) Appl. No.: **29/915,293**

(22) Filed: **Oct. 27, 2023**

(30) **Foreign Application Priority Data**

Apr. 28, 2023 (EM) 015020121-0005

(57) **CLAIM**

The ornamental design for a grille for automobile or replica thereof, as shown and described.

DESCRIPTION

FIG. 1 is a front, right isometric view of a grille for automobile or replica thereof;

FIG. 2 is a right side elevation view of FIG. 1;

FIG. 3 is a left side elevation view of FIG. 1;

FIG. 4 is a front elevation view of FIG. 1; and,

FIG. 5 is a top plan view of FIG. 1.

The evenly spaced broken lines in the drawings illustrate portions of the grille for automobile or replica thereof that form no part of the claimed design.

1 Claim, 5 Drawing Sheets
